(57) **CLAIM**

The ornamental design for a razor package, as shown and described.

DESCRIPTION

FIG. 1 is a front perspective view of the razor package;

FIG. 2 is a front view of the razor package;

FIG. 3 is a rear view of the razor package;

FIG. 4 is a right view of the razor package;

FIG. 5 is a left view of the razor package;

FIG. 6 is a top view of the razor package; and,

FIG. 7 is a bottom view of the razor package.

The broken lines in the drawings represent environmental subject matter and form no part of the claimed design.
